DESIGN FOR A RADIO RECEIVER CABINET

Horace Terrell, New York, N. Y., assignor to Espey
Manufacturing Company, Inc., New York, N. Y.,
a corporation of New York

Application December 13, 1944, Serial No. 116,879

Term of patent 3½ years

(Cl. D56—4)

To all whom it may concern:

Be it known that I, Horace Terrell, a citizen of the United States, residing at New York city, county of New York, and State of New York, have invented a new, original, and ornamental Design for a Radio Receiver Cabinet, of which the following is a specification, reference being had to the accompanying drawing, forming part thereof.

The figure is a perspective view of a radio receiver cabinet embodying my new design.

The rear portion and side portion, not shown, are plain.

I claim:

The ornamental design for a radio receiver cabinet, as shown and described.

HORACE TERRELL.
